UNITED STATES PATENT OFFICE

154,862

DESIGN FOR AN AIRPLANE

David W. Main, Denver, Colo.

Application February 8, 1947, Serial No. 136,793

Term of patent 14 years

(Cl. D71—1)

To all whom it may concern:

Be it known that I, David W. Main, a citizen of the United States, residing in the city and county of Denver and State of Colorado, have invented a new, original, and ornamental Design for an Airplane, of which the following is a specification, reference being had to the accompanying drawing, forming part thereof.

In the drawing:

Figure 1 is a front elevational view of an airplane embodying my design, said view being on a line slightly above the horizontal;

Figure 2 is a side elevation thereof;

Figure 3 is a plan view of same.

Figure 4 is a perspective view of the airplane looking from the lower left side toward the bottom;

Figure 5 is another perspective view of the airplane looking from the upper left side toward the top.

I claim:

The ornamental design for an airplane, as shown.

DAVID W. MAIN.
